UNITED STATES PATENT OFFICE

156,198

DESIGN FOR A COMBINED AUTOMOBILE HOOD, RADIATOR, AND HEAD LAMPS

William H. Burke, Alameda, Calif.

Application October 21, 1948, Serial No. 149,230

Term of patent 14 years

(Cl. D14—18)

To all whom it may concern:

Be it known that I, William H. Burke, a citizen of the United States of America, residing at Alameda, in the county of Alameda and State of California, have invented a new, original, and ornamental Design for a Combined Automobile Hood, Radiator, and Head Lamps, of which the following is a specification, reference being had to the accompanying drawing, forming a part thereof.

Fig. 1 is three-quarter front perspective view of the combined automobile hood, radiator, and head lamps, showing my new design.

Fig. 2 is a front elevation of the same, and
Fig. 3 is a top plan view thereof.

I claim:

The ornamental design for a combined automobile hood, radiator, and head lamps, substantially as shown.

WILLIAM H. BURKE.
